UNITED STATES PATENT OFFICE.

WILLIAM R. EVERETT, OF BENTON HARBOR, MICHIGAN, ASSIGNOR, BY MESNE ASSIGNMENTS, TO F. G. HOGLAND, OF ROCKFORD, ILLINOIS.

SPRING-MOTOR.

1,387,480.

Specification of Letters Patent. Patented Aug. 16, 1921.

Application filed June 27, 1918. Serial No. 242,160.

To all whom it may concern:

Be it known that I, WILLIAM R. EVERETT, a citizen of the United States, residing at Benton Harbor, in the county of Berrien 5 and State of Michigan, have invented a certain new and useful Improvement in Spring-Motors, of which the following is a specification.

My invention relates to that class of 10 motors which develop power from a spring or from a plurality of springs and more particularly to spring motors designed for the operation of phonographs and the like.

My object is to produce a construction 15 that will develop the maximum of power with the minimum of friction, the minimum of noise and the minimum of trouble, as will be hereinafter explained.

Motors for this purpose with which I am 20 familiar provide for the driving of the governor shaft from the turntable shaft. This arrangement is due to the necessity for obtaining a higher gearing ratio for the governor drive than would be practical to obtain 25 from the means of driving the turntable shaft, as such motors are commonly designed. With this construction, any varying or irregular motion or speed of the governor is transmitted directly to the turntable and thus seriously affects the tone production. 30

In my construction I provide an intermediate shaft placed at an angle both to the spring shaft and to the governor shaft. 35 This intermediate shaft is driven by the spring box gear and in turn drives, not only the turntable shaft, but also the governor shaft. By this construction it will be apparent that the governor shaft, turntable 40 shaft and spring box gear are, in effect locked together by reason of their respective gears being in mesh with gears on the intermediate shaft. It follows, therefore, that no change of speed in the governor can affect any single pair of gears without affecting all pairs. The result is, that each pair of gears acts to stabilize or to prevent any irregular motion of any of the other pairs, which results in a much more even rotation 45 of the turntable.

Governors for phonographs are almost universally placed with their shafts horizontal. They are so arranged because of the desirability of driving the governor with

helical gearing. With such construction, 55 however, the force of gravity tends to unbalance the governor by causing the weights to move out of a true circular path concentric with the axis of rotation. This condition results in vibration which is communicated to the gears, creating noise and wear and results, furthermore, in developing an irregular motion of the turntable.

Ordinarily the weights of the governor 60 are secured to flat springs. The constant flexing of these springs has a great tendency to loosen the means employed to fasten the ends into position with the result that as the ends become loose the governor becomes very noisy. 70

In addition to these objectionable features, the undue wear and noise resulting from the aforesaid causes is accentuated if the springs are of unequal weight and stiffness. If the springs are not all of equal tension then the 75 unfavorable conditions which tend to increase the noise and vary the speed, are aggravated.

In my improved form of construction, I 80 employ a vertical shaft for the governor and the weights are connected to links in place of the usual springs. Under this construction, the weights will all tend to swing in a true circle and to rotate the governor shaft about its axis free from any tendency 85 to make it wobble or set up an undulatory motion. I am able to revolve the governor around a vertical axis, independent of the turntable shaft, because the slant of my intermediate shaft creates a new condition 90 which makes it practical to use helical gearing of sufficient ratio.

Furthermore, in my construction, the thrust of the gearing, gravity and the pressure of the brake can be all in one direction 95 opposing the lift of the governor weights, whereas in the usual or horizontal axis construction, the thrust of the gearing is opposed to the brake pressure, and the force of gravity and the centrifugal force are exerted 100 in a different direction.

In this latter construction it is found, in operation these forces do not equalize; first one and then another becomes preponderant and the result is undue wear on the bearings 105 and objectionable noise.

My means of accomplishing the foregoing objects may be more readily understood by

having reference to the accompanying drawings which are hereunto annexed and are a part of this specification, in which:

Figure 1 is a vertical side elevation of my improved device.

Fig. 2 is a top or plan view of the same.

Fig. 3 is a fragmentary detail view having part of the frame broken away to show the interior connecting of the intermediate 10 shaft.

Fig. 4 is a top or plan view having the frame broken away to show the interior construction.

Fig. 5 is a fragmentary view.

15 Similar reference numerals refer to similar parts throughout the entire description.

As shown in the drawings, 6 is a winding shaft of the usual construction, which carries the spring boxes 7, to one of which is 20 secured the spring box driving gear 8, the driving shaft being suitably journaled in a frame 9 in the usual manner. The outer end of the spring is, of course, secured to the gear 8 in the usual manner. An intermediate shaft 10 is mounted in suitable journals 11 and 12, cast or formed on the frame 9. The intermediate shaft 10 is set at an angle to the turntable shaft and also diverges at an angle from the axis of the winding 25 shaft.

A spiral pinion 13 is secured to the intermediate shaft 10 in position to mesh with the teeth of the spring box driving gear 8. The turntable shaft 14 is suitably journaled 30 in the top wall 15 and bottom wall 16 of the frame 9, and is provided with a spiral pinion 17, the teeth of which mesh with the spiral gear 18 fixedly attached to the intermediate shaft 10. The governor shaft 19, which, as 35 is apparent from the drawings, is vertical, and parallel to the turntable shaft 14, is suitably journaled in the walls 15 and 16 of the frame 9. It is provided with a spiral pinion 20 which meshes with the spiral gear 21 carried by the intermediate shaft 10. From 40 this description, it is apparent that the governor shaft 19, turntable 14, and spring box driving gear 8, are all locked together through the medium of the respective gears 45 secured to the intermediate shaft 10.

The governor is of the usual centrifugal ball type and consists of a plurality of weights 22, which are connected to links 23 which are pivoted at one end to a collar 24 50 and at the other end to the hub 25, of a disk 26 which obviously is carried upward upon the shaft 19 when the speed of said shaft is increased, causing the weights 22 to swing outwardly.

60 A brake of the usual construction is provided and comprises a bell crank lever 27 which is mounted upon a pin or pivot 28 and is provided with a contact 29 made of felt or any other suitable material. When the up-

per end of the lever 27 is swung on its pivot 65 28, it is obvious that the contact 29 will be raised from the disk 26. This permits the latter to rotate up to such a speed that the upward pressure against the contact 29 results in sufficient friction to hold against any 70 further increase in speed.

This construction results in a very efficient and practically noiseless motor and is entirely immune from the troubles resulting 75 from the use of the usual spring governor set horizontally.

Although I have described a specific form of construction, it is understood this is merely for the purpose of illustrating the preferred embodiment, as various changes in 80 details may be employed in practice, and I do not desire to be limited to the specific details, except as such limitations shall appear in the hereinafter contained claims.

Having described my invention, what I 85 regard as new and desire to secure by Letters Patent, is:

1. The combination with a frame of a winding shaft, a plurality of coil springs 90 mounted thereon, a spur gear mounted on said shaft and suitably connected to said springs, a vertical turntable shaft, an intermediate shaft suitably journaled in said frame, and inclined from the axis of the turntable shaft and also diverging 95 from the axis of the spring shaft, a spiral gear on said intermediate shaft driven by said spur gear, a vertical turntable shaft, a spiral pinion on the turntable shaft, a spiral gear on the intermediate shaft which 100 meshes therewith, a vertical governor shaft, a spiral pinion thereon, a spiral gear on said intermediate shaft which meshes therewith, a ball governor on said governor shaft, a disk splined thereon, and a brake adapted to 105 engage said disk at a predetermined point.

2. The combination with a spring motor having a frame, winding shaft, and springs, a driving gear operated by said coil spring, an intermediate shaft set at an angle to the winding shaft in both the horizontal and vertical plane, a vertical turntable shaft, and a vertical governor shaft, spiral gears on 110 said intermediate shaft in mesh with spiral pinions on said turntable and governor shafts, a spiral pinion on said intermediate shaft which meshes with the spring driving gear, a ball governor on said governor shaft, and means to hold said shaft against rotation, said means being adapted to check its 115 rotation above a predetermined rate of speed.

3. The combination with a frame, of a winding shaft, a coil spring, a spur gear mounted on said shaft, one end of said spring being secured to said gear, an intermediate shaft suitably journaled in said frame, and inclined from the horizontal and also diverging at an angle from the axis of 120 125

the spring shaft, a spiral gear on said intermediate shaft driven by said spur gear, a vertical turntable shaft, a spiral pinion thereon, a spiral gear on the intermediate shaft which meshes therewith, a vertical governor shaft, a spiral pinion thereon, a spiral gear on said intermediate shaft which meshes therewith, a ball governor on said governor shaft, a disk splined thereon, and 10 a brake adapted to engage said disk at a predetermined point.

4. The combination with a spring motor for phonographs having a winding shaft, driving springs and spring box driving gears 15 mounted on said shaft, of a frame journal bearings for said shaft, a vertical governor, a turntable, a shaft crossing the governor and turntable shafts diagonally and meshing therewith, and actuated by the spring box driving gears to rotate both the turntable and the governor, means to hold said governor against rotation and means adapt-

ed to prevent the rotation of the governor above a predetermined rate of speed.

5. The combination with a spring motor 25 for phonographs having a winding shaft, driving springs, and spring driving gears mounted on said shaft, of a frame for said mechanism, bearings for said governor shaft, a turntable, a shaft which carries said turntable, a shaft which crosses the turntable shaft diagonally, gears mounted on said angular shaft, actuated by the spring driving gears, which rotate said shaft and gears mounted on said angular shaft to rotate the 30 turntable, and governor shafts, said gears serving to lock said shaft and spring driving gears together and means to prevent the rotation of the governor shaft above a predetermined rate of speed.

In testimony whereof I have signed the foregoing specification.

WILLIAM R. EVERETT.
